UNITED STATES PATENT OFFICE.

KENTON COOPER, OF MONROVIA, CALIFORNIA.

PAPER-HOLDER.

1,365,383.

Specification of Letters Patent. Patented Jan. 11, 1921.

Application filed June 14, 1920. Serial No. 388,870.

To all whom it may concern:

Be it known that I, KENTON COOPER, a citizen of the United States, residing at Monrovia, in the county of Los Angeles and 5 State of California, have invented a new and useful Paper-Holder, of which the following is a specification.

This invention relates to a holder for sheets of paper or the like and the invention 10 is useful in holding paper sheets of the type employed in wrapping fruit, as, for example, citrus fruit. An object of the invention in common with that of my prior Patent No. 763,045, dated June 21, 1904, is to 15 provide a holder adapted to be secured to a box in which are retained wrapping-papers for inclosing oranges, lemons or other fruit, the said box generally being placed upon the fruit box which is being packed with fruit, 20 or placed in close proximity to such fruit box.

An object of this invention in contradistinction to that of the former invention is to 25 improve the functioning of the device, especially to prevent lateral movement of the presser and binding of the presser when it is raised for the insertion of a new stack of wrapping papers.

Another object is to so construct the device 30 that the presser, when it is being raised for the insertion of the wrapping papers, cannot be pulled out of its socket.

Another object is to simplify the construction for holding the needle in place.

35 Other objects and advantages will appear hereinafter.

The accompanying drawings illustrate the invention:

Figure 1 is a perspective view of the invention as applied to a paper holding box, a fragment of which is also shown.

Fig. 2 is an enlarged front elevation of the holder shown in Fig. 1, a fragment of the box also being shown.

45 Fig. 3 is a front elevation similar to Fig. 2, excepting that the socket forming member and screws are shown in section and the spring extends into the body.

Fig. 4 is a plan section on line indicated 50 by $\alpha^4-\alpha^4$, Fig. 2.

Fig. 5 is an enlarged sectional detail of the socket end of the presser with the needle in place.

There is provided a socket forming member or body indicated in general by the character 1 and comprising a front plate 2, a back plate 3, side walls 4, 5 and a partition wall 6. The walls 2, 3, 4, 6 inclose a space forming a way 7 for a presser indicated in general by the character 8.

The front plate 2 and back plate 3 are provided with holes 9, 10 respectively through which extends a thumb screw 11. The front plate 2 is also provided with a hole 12 through which extends a thumb screw 13. The screws 11, 13 are adapted to screw into a suitable support formed, in the instance shown in the drawings, by the upright back wall 14 of a box 15 adapted to contain sheets of wrapping paper that are 70 indicated at 16.

The presser comprises an inverted U-shape member, the legs of which are indicated at 17, 18, and the leg-connecting member at 19. The presser also comprises a 75 third leg 20 extending parallel to the leg 18 and spaced slightly therefrom and connected with the leg 18 by a lower cross member 21. The legs 18, 20 and cross member 21 together constitute a U-shape member, and the legs 18, 20 are in a plane substantially at right angles to the plane occupied by the legs 17, 18. The legs 18, 20 slidably 80 fit in the way 7 and the screw 11 passes through the way between the legs 18, 20 so as to form a stop adapted to engage the cross member 21 to limit upward movement of the presser 8.

The leg 20 is connected at its upper end to the leg 18 by an upper cross member 22 90 which is coiled around the leg 18 to form an eye 23 through which the leg 18 extends. The free end of the member 22 forms a hook 24 to which is attached the upper end of a coil spring 25. The lower end of the coil spring 25 in Figs. 1, 2 and 4 engages an outstanding lug 26 which may be stamped from the front plate 2. This spring 25 tends to pull the presser down and retain it in the position shown in Figs. 2 and 3.

The lower end of the leg 17 is provided with a longitudinal slot 27 and the slotted end is provided with taper screw threads 28 so that a binding nut 29, engaging the screw-threaded end, will force the furcations 30 of the leg 17 toward one another and thus hold the furcations firmly against a needle 31 which may be inserted in a socket 33 formed in the lower end of the leg 17, the furcations 30 forming the walls of the socket. The furcations 30 may have the characteristics of spring material so as to tend to expand when the nut 29 is removed, thus freeing the needle 31.

15 The leg 20 prevents rotation of the leg 18 and thus lateral movement of the leg 17 cannot take place. It is to be noted that in the position shown in Fig. 2 of the drawings the spring 25 is substantially in front 20 of the leg 18 so that the power of the spring is exerted substantially in a vertical plane passing through the U-shape member 17, 18, 19, thus avoiding to a large extent the production of excessive friction and consequent binding between the leg 18 and the walls 25 4, 6.

In the instance shown in the drawings the socket member 1 is formed from a single piece of sheet or strip metal and the walls 5, 30 and 6 extend at right angles to the front and back plates 2, 3 respectively. The front and back plates are parallel with one another and the back plate is narrower than the front plate so that the walls 5, 6 are 35 spaced from each other, such space being indicated at 32. It is clear that if the user of the holder desires to have the spring 25 partly housed within the socket member 1, said spring may be unfastened at its lower 40 end from the lug 26 and it may be inserted into the space 32 and connected with the screw 13 as in Fig. 3 or the spring may be connected by any other suitable means with the socket member 1.

45 In practice, some packing houses will furnish the holders already attached to boxes adapted to hold the wrapping papers and, in other instances, the packers of the fruit will themselves furnish the holders, in 50 which latter case the fruit packer will fasten the holder to a suitable upright support which he will in turn fasten to a bench or other member capable of supporting the wrapping papers 16.

55 After the holder has been installed in a manner similar to the showing in Fig. 1, a package of sheets of wrapping paper will be placed in position to be retained by the needle 31 by the operator inserting a finger 60 beneath the cross member 19 and lifting upon the same to raise the presser sufficiently high to permit the insertion of a package of wrapping papers which he then pushes into place beneath the needle 31, whereupon he

will allow the presser to be drawn downwardly by the spring 25 to engage the upper sheets by the needle.

The needle 31 is positioned adjacent the rear edge of the package of wrapping papers and, when the fruit packer desires to 70 remove a sheet of paper from the package, he will pull the same toward him so as to cause it to tear adjacent the needle. As the sheets are gradually used, the spring 25 will gradually lower the presser so as to always 75 maintain the needle 31 in engagement with the upper sheets of the package of wrapping paper. When the fruit packer desires to transport the holder, he will unscrew the nut 29 and remove the needle 31.

80 When the fruit packer or other person is inserting the package of wrapping paper beneath the needle 31, it is impossible for him to pull the presser entirely out of the way 7, since I have provided for the screw 85 11 engaging the lower cross member 21 to limit upward movement of the legs 18, 20.

Although Figs. 1, 2 and 4 of the drawings disclose the spring 25 on the outside of the socket member 1, it is believed to be obvious 90 without further illustration that it may be positioned with its lower portion inserted in the space 32 in the manner shown in Fig. 3 and hereinbefore described. The holder above described works smoothly and is comparatively inexpensive to manufacture and it avoids some of the objections arising in the use of my prior invention hereinbefore referred to.

100 I claim:

1. In a paper holder, a body having a way, a presser shiftably mounted in the way and having a needle-holding leg and having a spring-engaging member offset laterally from the axis of the way, and a spring fastened at one end to the spring-engaging member and fastened at its opposite end to the body, the spring and needle-holding leg being substantially in a plane extending at 105 right angles to the plane of the way. 110

2. In a paper holder, a body having a way, a presser shiftably mounted in the way, means yieldingly holding the presser in paper-holding position, and a member mounted in the body and extending into the 115 way and adapted to engage the presser when the presser is moved a predetermined distance against the power of the spring, said member also constituting fastening means for securing the body to a support. 120

3. In a paper holder, a body having a way, a presser having a U-shape member mounted to shift in the way and having a leg connected with the U-shape member, the legs of the U-shape member being connected together near their upper ends by a cross member, said cross member forming an eye and one of the legs of the U-shape member 125

extending through said eye, said cross member forming a spring-engaging member at its free end, and a coil spring fastened to the spring-engaging member and connected 5 to the body.

4. In a paper holder, a body comprising front and back plates and side walls and a partition wall between and spaced from the side walls, a presser mounted to shift in the 10 body on one side of the partition wall, and

a spring connected at its upper end to the presser and having its lower portion retained in the body on the other side of the partition.

Signed at Los Angeles, California, this 15
4th day of June, 1920.

KENTON COOPER.
